THOMAS HENRY RAMMEL, OF PLAINVILLE, MASSACHUSETTS, ASSIGNOR TO WHITING & DAVIS COMPANY, A CORPORATION OF MASSACHUSETTS.

BAG CLASP.

Application filed February 7, 1922. Serial No. 534,692.

To all whom it may concern:

Be it known that I, THOMAS H. RAMMEL, a citizen of the United States, residing at Plainville, in the county of Norfolk, State 5 of Massachusetts, have invented certain new and useful Improvements in Bag Clasps; and I do hereby declare the following to be a full, clear, and exact description of the invention, such as will enable others skilled in 10 the art to which it appertains to make and use the same.

This invention relates to hand bags, purses and in general to bags of the type having frame members to which the material 15 composing the body of the bag is attached; and more particularly, the invention involves the provision of an improved clasp device for securing the frame members together when the bag is closed.

20 In accordance with the invention, the clasp includes in its construction a plurality of elements, movable one relative to the other, preferably in the form of a pair of pins, together with means such as a projection or 25 lug mounted on the other of the frame members which is adapted to coact with the clasp elements to secure the frame members together when the bag is closed. The clasp elements have their adjacent ends terminat- 30 ing in surfaces with which the clasp means mounted on the other frame member is adapted to coact to effect the locking together of the frame members. These terminal surfaces are preferably shaped in such 35 manner as to form a space for the reception of the cooperating locking lug, and the clasp elements or pins are normally positioned one relative to the other and are held by yieldable retaining means, such as a 40 spring, so as to provide a space slightly less than that requisite for the free passage of the lug. Thus, when in cooperative locking position with the pins, the lug is engaged by the terminal surfaces and is locked 45 thereby, and the frame members are firmly secured against opening. By subjecting the 50 pins to a slight pressure of the fingers, the pins may be moved axially relative to each other which results in separation of the 55 terminal surfaces and enlargement of the space between them, which, if made sufficient by continued pressure, will permit the free passage of the lug through the enlarged space and release the frame members

for opening. Since the clasp pins are normally held or pressed together in locking position, or in other words, in the position in which they are held by retaining means for coaction with the lug to grip the latter, a dependable clasp means is provided which 60 is positive in its action, and which, once snapped, will effectively lock the frame members together. This will be apparent from the fact that when the lug engages the terminal surfaces of the pins in the 65 locked position of the parts, any tendency for movement of the lug through the constricted space under a pressure exerted upon the frame members which might result in the release of the lug, would be resisted by the spring or other means for retaining the pins in normal position. The pressure on the pins resisting their separation is made sufficient to preclude the possibility of accidental opening of the bag by 70 outward pressure exerted upon the frame members, for example, by overloading the bag or otherwise; and, in fact, the pins are held against relative movement by pressure sufficient to make it difficult if not impossible to separate the frame members in 75 any other way than by forcibly separating the pins by the application of pressure on their ends in the manner intended for disengaging the lug and opening the bag. 80

The invention is illustrated in the accompanying drawings in application, as an example, to a hand bag or purse. In the drawings—

Fig. 1 is a view in elevation of the frame 90 of the bag with the clasp device mounted thereon.

Fig. 2 is a view along the line 2—2 of Fig. 1;

Fig. 3 is a view similar to Fig. 2 showing 95 the clasp device in open position.

Fig. 4 is a view along the line 4—4 of Fig. 2; and

Fig. 5 is a view along the line 5—5 of Fig. 3. 100

Referring to the drawings, the frame 6 of the bag consists of a pair of frame members 7 and 8 which are hinged together at 9, the hinges being provided with springs 10 which tend to force the frame members 105 apart and to hold them in open position. At the apex of the frame member 7 is a sleeve 11 within which is mounted a pair

of pins 12 and 13. Fitted within the sleeve 11 so as to be capable of sliding therein is a tubular member 14 which terminates at its outer end in a head 15 provided with a screw cap 16, the member being open at its inner end. The pin 12 is rigidly secured at the open end of the tubular member 14 and has a central opening 18 therein for receiving the prolongation or stem 19 of the pin 13. The pin 13 is mounted to slide within the tubular member 14 and both this member and the pin 13 have registering slots 20 and 21 respectively for receiving a stop 22 consisting of a pin fixed in the sleeve 11, the stop limiting the movement of the pin 13, and the tubular member 14 in an outward and inward direction. The outer end of the stem 19 has fitted thereto a cap 23 between which and the pin 12 and tubular member 14 is mounted a coil spring 24 surrounding the stem 19.

The pins 12 and 13 terminate in conical surfaces 25 and 26 respectively which form a space for receiving a lug or ball clasp 27 carried by the frame member 8.

The bail 28 of the bag is secured to the sleeve 11 and to the bail is fastened the usual chain or strap 29 by which the bag is carried.

30 The action of the clasp device is as follows: The spring 24, abutting at one end against the pin 12 and the tubular member 14 and at the other end against the cap 23, exerts an outwardly directed pressure upon 35 both the pin 12 and the pin 13, and these pins are thereby normally retained in a position abutting each other. This position of the pins, which is the locking position, is illustrated in Figs. 2 and 4. In this position the surfaces 25 and 26 of the pins are close together and the space formed between them is of a size slightly smaller than that which is required to permit the free passage 40 of the ball clasp 27. With the ball clasp disengaged from the pins in the open position, as illustrated in Fig. 3, if the frame members are brought together to close the bag and then forced together with a slight pressure of the fingers the ball clasp will snap 45 into locking position against the pressure of the spring 24, this position being illustrated in Fig. 2. When snapped into this locking position, the lug is firmly held by the surfaces 25 and 26 of the pins, the frame members are locked together and the bag is securely held against opening. The clasp device is operated to open the bag by applying 50 an inward pressure on the caps 16 and 23, this being conveniently done by grasping both these caps between the fingers and pressing inwardly upon them. By exerting pressure in this manner the pins are forced apart and moved one relative to the other axially to a position in which the surfaces 55 25 and 26 are separated and the space

formed thereby is enlarged an amount sufficient to permit the free passage of the ball clasp. The frame member 8 on which the ball clasp is mounted will then be released and the bag may readily be opened.

The bag is suspended for carrying it from a chain or strap which is secured to the bail 28.

I claim:

1. A bag frame comprising a pair of frame members, and a clasp device therefor including a plurality of elements movable axially one relative to the other and terminating in opposed surfaces, and means which is adapted to coact with said surfaces and to be engaged thereby to secure the frame members together in one position of said elements and to be disengaged to permit the frame members to be opened in other positions of said elements. 75

2. A bag frame comprising a pair of hinged spring-pressed frame members, resilient means carried by said members tending to open the latter, and a clasp device therefor including a pair of elements mounted on one of the frame members, which elements are movable axially relative to each other and terminate in opposed surfaces, and means carried by the other of said frame members which is adapted to coact with said surfaces and to be engaged thereby in one position of said elements, and to be disengaged to permit the frame members to be opened in other positions of said elements. 90

3. A bag frame comprising a pair of frame members, and a clasp device therefor including a pair of elements, mounted on one of the frame members, which elements are movable one relative to the other and terminate in opposed surfaces shaped to provide a space, and a projection carried by the other frame member positioned in alignment with said space, and which is adapted to be engaged by said surfaces in one position of said elements to secure the frame members together, and to be disengaged to permit the frame members to be opened when said elements are moved to other positions. 100

4. A bag frame comprising a pair of frame members, and a clasp device therefor including a pair of elements, mounted on one of the frame members, which terminate in opposed surfaces shaped to provide a space of a given size in the normal position of said elements, and which are movable axially relative to each other to vary the size of said space, means for yieldably retaining the said elements in their normal position, and a projection carried by the other frame member which is adapted to be engaged by said surfaces to secure the frame members together in the normal position of said elements, and to be released when said space is enlarged by axial movement of said elements to increase the distance between said surfaces. 115 120 125 130

5. A bag frame comprising a pair of frame members, a sleeve on one of the frame members, a projection on the other frame member, and a pair of elements mounted in the 5 sleeve and movable therein away from each other to provide a space between them through which the projection may pass, and toward each other to positions to coact with the projection to lock the frame members together.

6. A bag frame comprising a pair of frame members, a sleeve on one of the frame members, a projection on the other frame member, and a pair of elements mounted in the 15 sleeve and movable therein away from each other to provide a space between them through which the projection may pass, and toward each other to positions to coact with the projection to lock the frame members together, and a spring for holding the said ele-

ments close together with a yielding pressure.

7. A bag frame comprising a pair of frame members, and a clasp device therefor including a pair of pins mounted on one of the 25 frame members which terminate in opposed surfaces shaped to provide a space of a given size in the normal position of said pins, and which are movable axially relative to each other to vary the size of said space, spring 30 means for yieldably retaining said pins in their normal position, and a lug which is adapted to be engaged by said surfaces to secure the frame members together in the normal position of said pins, and to be released when said space is enlarged by relative movement of the pins to increase the distance between said surfaces.

In testimony whereof I affix my signature.

THOMAS HENRY RAMMEL.
